LOUIS E. MCQUAY, OF WEBSTER GROVES, MISSOURI, AND WILLIAM K. NORRIS, OF EAST ST. LOUIS, ILLINOIS.

PACKING-RING.

1,071,647.

Specification of Letters Patent. Patented Aug. 26, 1913.

Application filed May 1, 1913. Serial No. 764,770.

To all whom it may concern:

Be it known that we, LOUIS E. MCQUAY and WILLIAM K. NORRIS, citizens of the United States, said MCQUAY residing at 5 Webster Groves, St. Louis county, Missouri, and said NORRIS residing at East St. Louis, St. Clair county, Illinois, have invented certain new and useful Improvements in Packing-Rings, of which the following is a specification.

This invention relates to engines or devices of every kind in which a metal piston-head packing ring is used, and the objects attained by it are: first, to provide an absolutely leakable packing ring; second, to provide such a ring with a minimum of material and cost; third to construct the ring in the simplest manner, there being only two parts employed; fourth, to make a ring 20 which will be equally effective when used on the pistons, or piston heads of steam engines, steam pumps, air pumps or compressors, ammonia pumps or compressors, automobile, motorcycle, aeroplane or other engines, pending on the energy of steam, gas, gasoline, oil or other such agencies for power.

Further objects of this invention are to provide a packing ring in which the bands will have, approximately, equal tension, and 30 also in which the wear of the rings in the cylinder, will be uniformly distributed.

The device is fully illustrated in the accompanying drawing, in which—

Figure 1, shows a side elevation of an engine piston head equipped with several of the packing rings, in operative position. Fig. 2 is an enlarged side view with a portion of the outer band broken away, to show the construction behind it. Fig. 3 is a vertical section taken on the line 3—3 of Fig. 2, and Fig. 4, is a face view, on the scale of Fig. 3, showing a part of the exterior of a completed ring and under compression.

The various features of the device are referred to by numerals, like numerals denoting corresponding parts in the several views.

The numeral 6, designates the piston head of a gas engine, provided with our packing rings 8, which appear in edge view. These 50 rings are made in two members, or bands, each of which has an opening or split, 15, or 19, across it. These rings are expandable and resilient and are seated in the grooves in the piston head, by spreading them sufficiently to be slipped over the end of the

piston head and moved along to the grooves into which they spring, when released. Their expanding quality keeps their outer surfaces in sliding contact with the walls of the cylinder.

The inner band 14, of the device is of the full width of the ring and has an annular flange 16, projecting radially from the body of the ring at one of its edges. The outer band 18, of the ring is disposed in the angle 65 formed by the body of the inner band and the flange 16, and is flush with the flange on its peripheral surface and with the edge of the inner band, on its side. The split 15, in the band 14, and the split 19 in the band 18, are made in any preferred form, the inclined openings shown in the drawings being perhaps the best. These splits are positioned at any chosen part of the bands. The function of these splits is to render the bands 70 compressible and expansible, particularly the latter, to insure their pressure against the interior walls of the cylinder.

It is important that the bands 14 and 18, should be equal to each other in tension, or 80 as nearly equal as possible, the outer band being substantially three fourths of the width of the inner band, and the flange 16, of the inner band being substantially one fourth of the width of the inner band, so 85 that when placed together the combined width of the flange 16, and band 18, is equal to the total width of the whole ring.

In order to prevent any sliding of the bands, one upon the other, a radially outstanding peg 20, is provided on the body of the inner band, in lateral contact with its flange, of equal, or less height than said flange, and adapted to engage a notch 21, at one, or both inner corners of the split so as 95 to engage the peg at either corner, and so prevent any considerable rotation of the bands upon each other.

Having now described the invention and the manner of using it, what we claim and 100 desire to secure, is,—

1. A packing ring comprising an inner resilient split band, an annular radial flange on an outer edge of said band, an outer resilient split band disposed in the angle 105 formed by the body of the inner band and the flange thereon, the peripheral and the edge surfaces being flush with each other, the outer one of said bands being substantially three fourths of the width of the inner 110

band and the flange on the inner one of said bands being substantially one fourth of the width of the inner band, as herein set forth.

2. A packing ring comprising an inner 5 resilient band, a radial flange thereon, an opening through said band, a radial peg outstanding from the body of said inner band adjacent the flange thereof, an outer resilient band overlying said inner band, its 10 inner edge engaging the flange on said inner band, an opening through said outer band, the inner edge of said outer band at its opening, having a notch to engage said peg, the

outer one of said bands being substantially three fourths of the width of the inner band, ¹⁵ and the flange of the inner one of said bands being substantially one fourth of the width of the inner band.

In testimony whereof we affix our signatures in presence of two witnesses.

LOUIS E. McQUAY.

WILLIAM K. NORRIS.
